UNITED STATES PATENT OFFICE.

CHARLES H. NESSELROAD, OF STUART, IOWA.

BUILDING-BLOCK AND CHIMNEY.

SPECIFICATION forming part of Letters Patent No. 792,342, dated June 13, 1905.

Application filed January 11, 1905. Serial No. 240,600.

To all whom it may concern:

Be it known that I, CHARLES H. NESSELROAD, a citizen of the United States, residing at Stuart, in the county of Guthrie and State of Iowa, have invented new and useful Improvements in Building-Blocks and Chimneys, of which the following is a specification.

My invention pertains to building-blocks, more particularly blocks for building chimneys and the like; and it consists in the peculiar and advantageous blocks and chimney hereinafter described and particularly pointed out in the claims appended.

In the accompanying drawings, forming part of this specification, Figure 1 is a perspective view of so much of a chimney as is necessary to illustrate my invention. Fig. 2 is a vertical section of the same. Fig. 3 is a top plan view of one course of blocks. Fig. 4 is a perspective view of one of the right blocks of the chimney removed, and Fig. 5 is a similar view of one of the left blocks.

Similar letters designate corresponding parts in all the views of the drawings, referring to which—

A is the main portion of my novel chimney, and B is the cap thereof.

As best shown in Fig. 1, the main portion A of the chimney is composed of courses of building-blocks C, of concrete or other fire-resisting material, and the blocks of one course are arranged opposite to the blocks of the adjacent course or courses—i. e., the blocks of one course are rights and the blocks of the adjacent course or courses lefts—this in order to break joints around the corners of the chimney, and thereby contribute materially to the stability and durability of the chimney as a whole.

The blocks C are similar in construction except that some are rights and some lefts, and therefore a detailed description of the blocks shown in Figs. 4 and 5 will suffice to impart a definite understanding of all. The said blocks, Figs. 4 and 5, respectively, comprise an exterior body portion *a*, having an angular arm *b* at one end and also having grooves *c* in its lower and upper edges extend-

ing throughout its length and designed to receive mortar or the like, as presently explained, and an interior body portion *d* extending above the exterior portion *a* and arranged with its lower edge above that of said exterior portion, whereby the exterior portion below the interior portion constitutes a flange *e*, and having a dovetail tenon *f* at its outer end extending beyond the adjacent end of portion *a*. Between the inner end of the interior body portion *d* and the arm *b* of the exterior portion *a* a dovetail groove *h* is formed, said groove being designed to receive the tenon *f* of a complementary block, as best shown in Fig. 3.

In constructing a chimney of my novel blocks four blocks C, left blocks—such as shown in Fig. 5, for instance—are placed with their tenons *f* in the grooves *h* of their complements, as shown in Fig. 3, and with this done it will be observed that the blocks will be locked together of themselves and that each side of the course will be formed by the body of one block and the arm of the next adjacent block. Mortar or the like *k* is then placed in the grooves of the blocks comprised in the course mentioned, and the blocks of the next upper course, which are preferably right blocks, such as shown in Fig. 4, are assembled and connected on the first-mentioned course in the manner shown in Figs. 1 and 2. When the courses are thus superposed, it will be observed that the interposed mortar *k* will connect the courses and act as a key between the same, also that the upward extensions of the inner portions of the lower blocks resting within the flanges *e* of the upper blocks will preclude lateral movement of the courses with respect to each other, and hence will lend great strength and rigidity to the chimney as a whole. It will further be observed that by reason of the dovetail groove of each block being formed between the inner end of the inner body portion and the arm of the outer body portion the outer wall of said groove is of considerable thickness, and hence is possessed of great strength and is capable of withstanding great lateral strain. Moreover, it

will be noted that the blocks are light in weight and compact, and hence may be handled and positioned by the mason with but little effort.

5 The blocks C may be of any height or width compatible with the purposes of my invention without involving a departure from the scope thereof. I prefer, however, to make the blocks four inches wide, which is the standard width of bricks, this in order that the 10 blocks may be used in repairing a brick chimney and the faces at the outer and inner sides of the chimney may be preserved.

15 While I prefer to make the several blocks comprised in the chimney of a uniform width or height, I do not desire to be understood as confining myself to the same, inasmuch as the blocks may be made of different widths or heights without departing from my invention or affecting the strength and durability of the 20 chimney.

25 It is apparent that the cap B (shown in Figs. 1 and 2) might be formed of four blocks constructed in accordance with my invention without departing from said invention. I prefer, however, to construct the cap in the manner illustrated—*i. e.*, of a lower course of blocks *m*, an intermediate course of blocks *n*, and an upper course of blocks *r*, all of said blocks being similar to the blocks C, except in shape 30 and size.

35 When it is desired to divide my improved chimney into two flues, lapped blocks C', such as shown in Fig. 2, may be employed, the said blocks being arranged one above the other in vertical grooves in the inner sides of opposite blocks C.

40 It will be gathered from the foregoing that my novel blocks are susceptible of cheap production in molds or otherwise and are so compact as to take up but a minimum amount of space in storage or shipment.

45 It is obvious that when desired certain of the blocks entering into the chimney may be provided with a pipe-hole and an opening for the reception of a soot-box; but I have deemed it unnecessary to illustrate these features.

50 I have entered into a detailed description of the construction and relative arrangement of parts embraced in the present and preferred embodiment of my invention in order to impart a definite understanding of the said embodiment. I do not desire, however, to be understood as confining myself to the said specific construction and relative arrangement of 55 parts, as such changes or modifications may be made in practice as fairly fall within the scope of my invention as claimed.

60 Having described my invention, what I claim, and desire to secure by Letters Patent, is—

1. A building-block comprising an exterior body portion having an arm at one end, and

an interior body portion extending above the exterior portion and arranged with its lower edge above that of said exterior portion and 65 having a tenon at its outer end and also having its inner end arranged at a distance from the arm of the exterior portion, whereby a groove is formed between the two.

2. A building-block comprising an exterior 70 body portion having an arm at one end the inner side of which is shaped to form one wall of a dovetail groove, and an interior body portion extending above the exterior portion and arranged with its lower edge above that of 75 said exterior portion and having a dovetail tenon at its outer end and also having its inner end shaped to form the opposite wall of the said dovetail groove.

3. A building-block comprising an exterior 80 body portion having an arm at one end, the inner side of which is shaped to form one wall of a dovetail groove, and also having grooves in its upper and lower edges extending throughout the length thereof, and an interior 85 body portion extending above the exterior portion and arranged with its lower edge above that of said exterior portion and having a dovetail tenon at its outer end and also having its inner end shaped to form the opposite 90 wall of the said dovetail groove.

4. A building-block comprising a body having an arm at one end extending throughout its height, a tenon at its opposite end, extending throughout its height and arranged intermediate its vertical sides and in the same vertical plane as the arm, and a groove at the inner side of the arm adapted to receive the tenon of a complementary block.

5. A building-block comprising a body having a depending flange, an upwardly-extending inner portion, an arm at one end, a tenon at the opposite end, arranged in the same vertical plane as the arm, and a groove at the inner side of the arm adapted to receive the 105 tenon of a complementary block.

6. In a chimney, the combination of superposed courses of blocks; the blocks of the courses being relatively arranged to break joints around the corners of the chimney, and each block comprising a body having an arm at one end, a tenon at its opposite end, arranged in the same vertical plane as the arm, and a groove at the inner side of the arm receiving the tenon of a complementary block. 110

7. In a chimney, the combination of superposed courses of blocks; the blocks of the courses being relatively arranged to break joints around the corners of the chimney, and each block comprising a body having a depending exterior flange, an upwardly-extending inner portion, an arm at one end, a tenon at the opposite end, arranged in the same vertical plane as the arm, and a groove at the in- 115

ner side of the arm receiving the tenon of a complementary block.

8. In a chimney, the combination with superposed courses of blocks; of lapped partition-blocks arranged in grooves in opposite blocks of the courses and dividing the chimney into flues.

In testimony whereof I have hereunto set my hand in presence of two subscribing witnesses.

CHARLES H. NESSELROAD.
